United States Patent

Des. 239,659
Patented Apr. 20, 1976

239,659

ELECTROSTATIC COPYING MACHINE OR SIMILAR ARTICLE

Isao Katayama, Sakai, Osaka, and Sadao Ishihara, Yao,
Osaka, Japan, assignors to Minolta Camera Kabushiki
Kaisha, Azuchi, Osaka, Japan

Filed Sept. 3, 1974, Ser. No. 499,676

Claims priority, application Japan Feb. 22, 1974

Term of patent 14 years

Int. Cl. D16—05

U.S. Cl. D16—31

FIG. 1 is a front elevational view of an electrostatic copying machine or similar article embodying our new design.

FIG. 2 is a rear elevational view thereof.

FIG. 3 is a left side elevational view thereof.

FIG. 4 is a right side elevational view thereof.

FIG. 5 is a plan view thereof; and

FIG. 6 is a bottom plan view thereof.

We claim:

The ornamental design for an electrostatic copying machine or similar article, as shown.
